UNITED STATES PATENT OFFICE

JOSEPH P. MCENERY, OF FLUSHING, NEW YORK

PENCIL HOLDER

Application filed December 30, 1930. Serial No. 505,539.

This invention relates to pencil holders and the like and has for an object an inexpensive, efficient and serviceable combined pencil holder and clip for attaching the same to an object such, for example, as a folded score card, dance program or the like in such manner that the card is held closed by the clip and the pencil is covered by the card.

A device embodying the invention comprises a pencil holder and a pair of clip arms attached thereto, the relation of the holder to the arms being such that the pencil extends between the sides of the folded article and the clip arms overlie the sides of the article to hold the same in closed relation. The clip arms may be movable relative to the pencil holder and to each other to lie either co-extensively with the pencil or in alignment with the same in non-writing or writing position respectively or the holder and clip arms may be fixed with respect to each other and the pencil be of sufficient length to extend beyond the ends of the clip arms. In either case, the pencil projects between the sides of the folded article which are held closed by the clip, thus effecting a compact arrangement of the folded article and pencil in which the pencil is securely and conveniently attached to the article and the latter is prevented from accidentally opening. By means of this arrangement, much of the inconvenience normally incident to the keeping of scores and the like is avoided inasmuch as the pencil is always readily available.

Other objects, novel features and advantages of this invention will be apparent from the following specification and accompanying drawings, wherein:

Fig. 1 is a perspective view of a score card having attached thereto a device embodying the invention.

Fig. 2 is a side view of such a device.

Fig. 3 is a plan view of Fig. 1.

Fig. 4 is a plan view of the device.

Fig. 5 is a fragmentary section on the line 5-5 of Fig. 3.

Fig. 6 is a section on the line 6-6 of Fig. 5.

Fig. 7 is a fragmentary section on the line 7-7 of Fig. 6.

Fig. 8 is a perspective view of a score card

provided with a modified form of the invention.

Fig. 9 is a side view of the device.

Fig. 10 is a plan view of Fig. 8.

Fig. 11 is a perspective view of the device 55 without a pencil.

Fig. 12 is a perspective view of a score card provided with a modified form of the invention.

Fig. 13 is a side view of the device.

Fig. 14 is a plan view of Fig. 12.

Fig. 15 is a partial section on the line 15-15 of Fig. 13, and

Fig. 16 is a section on the line 16-16 of 65 Fig. 13.

Throughout the following description and claims wherever the word "pencil" is used, it is to be understood that any other object which it would be helpful or desirable to have mounted in the same manner may be substituted for the pencil and where "writing purpose" or "writing position" is used, it is to be understood that any other purpose and similar position of use may be substituted as 70 would conform to the use of the substitute article.

Referring now more especially to Figs. 1 to 7 inclusive, the score card or the like 10 comprises a strip of cardboard folded in the middle to form sides 11 and 12. A short pencil or other article 13 having a pointed end and being preferably flat is mounted in the holder 14 which comprises a sheet metal member of the shape shown in Fig. 7. A pair of 80 clip arms 15 are pivotally supported by the holder 14. Each arm 15 comprises a length of wire bent into substantially U-shape and provided at its ends with inwardly projecting pintles 16 which extend through apertures 90 provided in the holder 14. The inner end of one pintle of each clip arm is bent at right angles to form a lug 17. Tongues 18 are struck out of the holder 14 and bent inwardly 95 in position to be engaged by the lugs 17. Each tongue is provided with inwardly offset projections 19 with which the lugs 17 engage when the arms are either in the position shown in full lines in Fig. 4 or in the position shown in dotted lines in the same fig- 100

ure, thereby exerting tension on the arms tending to hold them in contact and to oppose movement of them from such positions.

In this modification, the pencil 13 is of less length than the arms 15 so that when the arms are in the position shown in Fig. 2, the pencil is completely surrounded by the arms and is in what is termed "non-writing" position. To bring the pencil into writing position, the clip arms 15 are swung around into the position shown in dotted lines in Fig. 4, whereupon the pencil point is exposed and the pencil may be used in the ordinary manner.

The device is applied to a score card or the like as shown in Fig. 1. The clip arms move relative to each other sufficient to allow them to overlie the plies of the card and the pencil extends between the two plies. The clip arms hold the plies of the card together and also securely hold the pencil between the sides of the card, thus preventing accidental removal of the pencil as well as accidental opening of the card. A slight pull on the holder is sufficient to remove the device from the card after which the pencil may be brought into writing position as previously described.

In Figs. 8 to 11 inclusive, the pencil holder and clip arms are composed of a single length of wire as is clearly shown in Fig. 1. The clip arms comprise the U-shaped portions 20 and the pencil holder comprises the loop portion 21. The ends of the wire are soldered or welded together and to the holder 21 as at 22 and the offset portions of the arms are also soldered or welded together as at 23. The pencil 24 is slightly longer than the arms 20 and at the end opposite its point is provided with a pair of grooves in which are received the vertical portions of the loop 21. The pencil is introduced into the loop merely by sliding it through the same until the grooves register with the cooperating portion of the loop. Sufficient friction is thus supplied to prevent accidental withdrawal of the pencil.

In Figs. 12 to 16 inclusive, the pencil holder and clip arms are composed of a single piece of sheet metal. The pencil holder comprises an elliptical loop 25 from one end of which the clip arms 26 are bent to overlie the holder in spaced relation thereto. The pencil used with this form of the device is slightly reduced at the end which projects into the holder so that the outer surface of the pencil and the outer surface of the holder are continuous. This arrangement is clearly shown in Fig. 15.

When this device is attached to a score card as shown in Fig. 12, the sides of the card project into the space between the holder and the arms, (see Fig. 15) so that the pencil is contained substantially wholly within the score card and the holder itself

extends beyond the edge of the card only a distance very slightly greater than the width of the metal of which it is composed. This arrangement obviates any substantial projection beyond the edge of the score card and produces an extremely compact arrangement.

With each of the last two described modifications, the pencil is in fixed relation to the clip arms and is of sufficient length to project beyond the ends of the clip arms. The pencil is immediately available upon withdrawing the device from the score card. Also, in both of these modifications, the pencil is arranged between the plies of the score card when the device is applied to the same. The plies of the score card are held together by the clip arms and sufficient friction is exerted to prevent accidental removal of the holder.

It is of course understood that various modifications may be made in the device above described, without in any way departing from the spirit of the invention as defined in the appended claims. Moreover, it is apparent that the device may be put to many other uses than the use specifically described in the specification and that the scope of the invention is in no way limited except by the claims.

I claim:

1. A device of the character described comprising a pair of clip members and a holder for a pencil or other implement of similar shape carried by said clip members, said clip members being attached adjacent their ends to said holder and arranged to overlie a pencil or other implement carried by said holder.

2. A device of the character described comprising a holder for a pencil or other implement of similar shape, a pair of clip arms rigidly attached to said holder and embracing the pencil or other implement carried by said holder.

3. A device of the character described comprising a holder for a pencil or other implement of similar shape, and a pair of clip arms attached at their ends to said holder and embracing the pencil or other implement, said clip arms being adapted to clasp the plies of a folded article with the pencil or other implement interposed therebetween.

4. A device of the character described comprising a holder, a pair of clip arms integral therewith, and a pencil or other implement of similar shape carried by said holder between said arms and projecting beyond the ends of said arms, said clip arms being adapted to clasp the plies of a folded article with the pencil or other implement interposed between said plies.

5. A device of the character described comprising a holder and clip arms formed from a single piece of wire, and a pencil or other

implement of similar shape carried by said holder, said pencil or other implement being arranged between said clip arms and projecting beyond the ends thereof.

5 6. A device of the character described comprising a single piece of wire bent to form a loop and arms projecting from said loop, and a pencil or other implement of similar shape held within said loop between said arms and 10 projecting beyond the ends thereof.

7. A device of the character described comprising a single piece of sheet metal bent to form a holder and a pair of arms overlying the holder, a pencil or other implement of 15 similar shape carried by said holder between said arms and projecting beyond the ends thereof.

8. A device of the character described comprising a single piece of sheet metal shaped 20 to form a tubular holder and a pair of arms connected to the holder at one end and overlying the holder, and a pencil or other implement of similar shape carried by said holder and extending in the same direction as said 25 arms.

9. A device of the character described comprising a holder for a pencil or other implement of similar shape, and a pair of clip members pivotally attached thereto for movement 30 relative to each other and to the holder, said 95 clip members being adapted in one position to embrace the pencil or other implement and in another position to constitute an extension thereof.

35 10. A device of the character described comprising a holder for a pencil or other implement of similar shape, a pair of clip members pivotally attached to said holder, and means tending to urge said clip members to 40 100 toward each other to embrace said pencil or other implement or to constitute an extension thereof.

11. A device of the character described comprising a holder for a pencil or other implement of similar shape, a pair of clip arms 45 pivotally attached thereto, a lug carried by each of said arms, and resilient members extending from said holder into engagement with each lug to urge said arms into contact 50 with each other.

12. A device of the character described comprising a holder for a pencil or other implement of similar shape, a pair of clip arms 55 pivotally attached thereto, a lug carried by each of said arms, and a pair of tongues struck out from said holder and extending into engagement with said lugs to maintain said arms under stress toward the axis of the 60 holder.

13. A device of the character described comprising a holder for a pencil or other implement of similar shape, a pair of clip arms 65 pivotally attached to said holder, and means for exerting pressure on said clip arms to

maintain them either in substantial alignment with the pencil or other implement.

In testimony whereof, I have signed my name to this specification.
